UNITED STATES PATENT OFFICE.

RUDOLPH LIEBMAN, OF NEW YORK, N. Y.

BUTTON.

SPECIFICATION forming part of Letters Patent No. 390,869, dated October 9, 1888.

Application filed July 20, 1888. Serial No. 280,465. (No model.)

To all whom it may concern:

Be it known that I, RUDOLPH LIEBMAN, a citizen of the United States, residing at New York, in the county and State of New York, have invented new and useful Improvements 5 in Buttons, of which the following is a specification.

This invention has for its object to provide a novel button for garments, which can be attached quickly and conveniently, and which is strong, durable, and efficient, and is so constructed that when attached its fastenings will be concealed and able to resist the usual strains to which buttons are subjected. This object 15 I accomplish by the features of construction hereinafter described, and specifically pointed out in the claim, reference being made to the accompanying drawings, in which—

Figure 1 is a sectional view of a button embodying my invention; Fig. 2, a detail view 20 of the attaching-wire, and Fig. 3 a perspective view looking at the metallic back-plate of the button.

Similar letters indicate corresponding parts. 25 In the drawings, the letter A designates the head of the button, and B is its back-plate, which can be secured to the head in any well-known manner. In the back-plate are formed two perforations, a and b, which are located 30 near to the periphery of the same and are preferably placed diametrically opposite to each other. The ends of a wire, C, which is bent in the form shown in Fig. 2, are passed through said perforations, and the shorter exterior end is bent outward and upward to form 35 a hook, c. The larger exterior end, d, of the wire, which is made pointed, is bent back upon itself, so that it can be made to engage with the hook c, in the manner of a safety-pin. The 40 wire C is made of a flexible material, and the portion of the same lying within the button is soldered or otherwise secured to the inner surface of the back-plate B, so as to prevent the fastener from turning laterally. After the 45 wire C has been properly applied to the back-plate, the latter and the head A are united in any well-known manner. A suitable filling,

as e, can be first placed between the head and the back-plate.

I am aware that buttons have been provided 50 with attached safety-pins; but in one case the wire extends through the head of the button and mars the same, and in another case additional parts are used to secure the pin to the button.

In my button the attaching-wire lies between 55 the button head and back-plate, and consequently does not mar the head, and no additional parts are used to attach the pin to the button.

The perforation of the metallic back-plate at the points a b places such perforations within the circumference of the back-plate, so that the attaching-wire passing through said perforations is not exposed at the periphery of 65 such plate or at the periphery of the button. This is important, first, to conceal the attaching-wire, and, second, to so place and locate it that it will in no way interfere with the engagement and disengagement of a button-hole 70 with the button-head.

What I claim as new, and desire to secure by Letters Patent, is—

An improved article of manufacture, a button for button-holes, consisting of the button-head A, the flat metallic back-plate B, having 75 its edge rigidly fixed to the button-head, and provided with two perforations, a b, diametrically opposite each other, and located entirely within the circumference of the plate, and the attaching-wire placed inside the back-plate, 80 projecting rearward through the said perforations within the circumference of the back-plate and having its ends formed, respectively, into the hook c and pointed pin d, substantially as shown and described.

In testimony whereof I have hereunto set my hand and seal in the presence of two subscribing witnesses.

RUDOLPH LIEBMAN. [L.S.]
